CATHODE RAY TUBE

Harry R. Lubcke, Los Angeles, Calif.

Application June 16, 1933, Serial No. 676,078

5 Claims. (Cl. 250—27.5)

In this specification, and the accompanying drawing, I shall describe and show a preferred form of my invention, and specifically mention certain of its more important objects. I do not limit myself to the forms disclosed, since various changes and adaptations may be made therein without departing from the essence of my invention as hereinafter claimed; and objects and advantages, other than those specifically mentioned, are included within its scope.

My invention relates to electron emitting devices, and particularly to such types of cathode ray tubes as are adapted for television and oscillographic purposes. Among the salient objects of the invention are; first, to simplify and improve such devices, by providing a new type of cathode that is adapted to restrict the electronic emission to a single desired direction, and which may be operated directly by alternating electrical energy; second, to provide a new type of grid that is adapted to greatly reduce the input capacitance of devices of this kind; third, to provide a new type of anode that is adapted to focus an electronic stream in a new and improved manner, so as to make it unnecessary to use the now commonly employed interior plating of the glass envelope, and which does not require the presence of gas in the tube; fourth, to provide a new and improved shape and arrangement of deflecting plates in cathode ray tubes; fifth, to secure greater response of fluorescent screens to cathode rays than can be accomplished in hitherto known ways; and, sixth, to supply a new and improved means for maintaining a constant focus of an electronic stream, regardless of changes in its intensity.

My objects have been attained in the manner illustrated in the accompanying drawing, in which—

Figure 1 shows, diagrammatically, a cathode ray tube that embodies the elements of my invention, and indicates the manner in which this tube may be connected to standard thermionic and other electrical equipment, for securing the desired results; and

Figure 2 shows an alternative arrangement of the elements of my invention that may be used in such a tube.

My improved cathode preferably takes the form of a deeply cupped conducting annulus. This has an outer cylindrical portion 5; and an inner cylindrical portion 6 of smaller diameter, coaxial with the outer portion and spaced therefrom. One pair of the extremities of these coaxial tubes are conductively connected, by means

of a hollow truncated conical portion 7. Thus one end of the cathode is given the shape of a protruding truncated cone. The co-axial cylindrical portions necessarily are somewhat displaced with respect to each other in a longitudinal direction, and their respective lengths are such that the free end of the outer portion, extends considerably beyond the free end of the inner portion. A preferred method of constructing this cathode is to form it, as by means of proper dies, from a single integral piece of sheet nickel or other suitable metal. Such a cathode may be supported in a glass envelope 8 of a cathode ray tube, by means of conductors 9 and 11, sealed in the glass in the usual manner. Conductor 9 is electrically connected to the free extremity of outer portion 5 of the cathode, and conductor 11 is connected to the free extremity of inner portion 6. These conductors are utilized for carrying the heating current to the cathode, as from a battery 12 or other suitable source of energy.

It will be appreciated that, inasmuch as Fig. 1 is diagrammatic only, the proportions of the parts are shown somewhat exaggerated. The cathode, comprising elements 5, 6, and 7 is, in fact, relatively small; and it may be heated electrically, without difficulty. Inner cylinder 6, being of smaller cross-sectional area, and because of its inner location, will reach the highest temperature; the outer cylinder 5 will act as a thermal shield, and effectively decrease the rate of radiation of heat from the hotter inner cylinder. It will be appreciated further that the cross sections of the tubular portions 5 and 6 may be square or any other shape desired.

The described construction makes the cathode very efficient so far as consumption of heat energy is concerned, and it provides a very simple and convenient path for the heating current. The inner surface of inner cylinder 6, is coated with suitable electron-emitting material, such as barium oxide.

In my improved cathode, the maximum rate of electron emission may be made to occur at the junction of cylinder 6 and cone 7, by suitably proportioning the thickness and size of the various portions in ways that are well understood; and the electrical resistive center of the cathode also may be located at this junction. When this is done, it is entirely feasible to employ a source of alternating current in place of battery 12.

The electronic emission from my cathode will take place as if from a unipotential surface; thus accomplishing in a unitary cathode, what has hitherto required the use of a unipotential cath-

ode and a separate heater. Thermal inertia keeps the emitting surface at a substantially constant temperature, notwithstanding the instantaneous variations of heating energy when alternating current is used. It will be seen that the location of the electron-emitting material (only on the inner surface of cylinder 8) and the physical form of the cathode, will restrict the emission of electrons in such a manner as to produce a single 10 electronic stream, thus eliminating the necessity for using an electron-restricting electrode. In alternating current operation, my single cathode is capable of performing the function of the three electrodes that hitherto have been necessary for 15 accomplishing the same result.

The intensity of the electronic stream is controlled in my improved tube, by varying the potential of a grid 13 in the usual manner, the potential of the grid commonly being negative with 20 respect to the cathode. My preferred grid, however, takes the form of a hollow truncated cone, with its apex toward the cathode; and it is relatively small. This grid is supported in tube 8 by means of a conductor 14, which passes through 25 the wall of the glass envelope, and is sealed thereto. This support wire preferably leads through the envelope separately, for convenience in keeping the capacitance to ground small.

The conical grid shape, and the described arrangement, provides a minimum capacitance and a maximum control constant. It is well known that the closer that a grid is located to the cathode, the greater will be its controlling effect; and, since a cathode ray tube is a voltage-operated 35 device, it is desirable to keep the control coefficient high. The point where the maximum control effect upon the electronic stream is exerted, is the truncated apex of the grid. This is the part that approaches the cathode most closely, and the distance between these two elements may be made very small. In a grid of circular cross-section, such as the usual wire employed for that purpose, the theoretical point of control is at the center of its cross-section; and it necessarily has to be located, for this reason, further away from the cathode than the controlling apex of my improved grid construction.

As a part of the anode of my device, I prefer to employ a conducting tube 15; having an integral circular shield 16 thereupon, near the longitudinal center, for removing stray electrons in its vicinity. The location of this shield, and the conical shape of the cathode extremity 7, make the grid to ground capacitance relatively small. 55 The portion of the effective anode just described is maintained in its position in tube 8, and is operatively connected in circuit, by means of conductor 17 which passes the wall of the tube and is sealed thereto.

In addition to anode elements 15 and 16, I employ a separate perforated disk anode element 18, supported in place and connected in circuit by conductor 19. The gun anode element 18 is given the highest potential in the system, where- 65 by it is able to greatly accelerate the electronic stream passing therethrough. Disk 18 has a central hole 21, of larger diameter than the bore of tube 15, its potential is made approximately half that of portion 15, and it is slightly spaced from 70 the discharge end of this gun anode. The described arrangement makes it possible to further concentrate the electronic stream, by means of the radial field of force, which is of negative polarity, exerted between the margins of hole 21 and portion 15. This force opposes any tendency

of individual electrons to depart from the electronic stream because of their mutual repulsion. Thus, the usual dispersive effect, tending to produce a relatively large spot on the fluorescent screen, may be wholly overcome; and a minimum screen spot may be secured, by adjusting the potential of disk anode 18.

The concentration method just described is operative and effective under a high vacuum, and the cathode ray tube may be pumped to the highest evacuation obtainable, without incurring any of the undesirable features of high vacuum tubes that hitherto have been experienced. Also the disadvantages of short life and the necessity for adjusting the pressure during manufacture, hitherto accompanying the use of low vacuum tubes, may be eliminated.

Plate electrodes, for deflecting the electronic stream up and down, i. e., in the plane of the paper, are indicated at 22 and 23. It is well known that the closer such plates are to each other, the greater will be their deflecting effect; but, on the other hand, if they are too close, they will physically obstruct the electronic stream at the extremes of its deflection, thus reducing the effective working area of the fluorescent screen. It has been common practice hitherto, to employ parallel deflection plates that are rather widely spaced, so as not to interfere with the electronic stream at its maximum deflection. In my im- 30 proved construction I employ diverging plates, these being much closer together at their initial edges than at their final edges. Thus, a strong deflective action is secured where the electronic stream enters the deflecting field (at which point it has no deflection); and the wide spacing at the final edges of the plates, prevents obstruction of the stream at its maximum deflection.

Deflecting plates 22 and 23 are adapted for deflecting the electronic stream up and down only, 40 i. e., in the plane of the paper, to the limits of the final spacing of these plates. They are unable, however, to cause any deflection in a plane perpendicular to that of the paper. Consequently they may be made quite narrow, being merely 45 wide enough to prevent their edge effects from influencing the electronic stream. Making these plates narrow will lower the capacitance between them, and this is very desirable in oscillographic work. Plates 22 and 23 are supported in the 50 cathode ray tube 8, by means of conductors 24 and 25, leading to them respectively through, and sealed into, the glass wall of tube 8.

Deflecting plates 26 and 27 are used for deflecting the electronic stream in a horizontal 55 plane, i. e., perpendicular to the plane of the paper. These also are diverging for reasons similar to those stated. The spacing between these plates at their initial edges, is no greater than the spacing between the initial edges of plates 60 22 and 23; and the spacing at their final edges is made such as not to interfere with the electronic stream at its maximum horizontal deflection. Plates 26 and 27, instead of being made rectangular and narrow, are trapezoidal in form 65 as indicated, the divergence between the top and bottom edges being the same as the divergence between plates 22 and 23, for obvious reasons. Plates 26 and 27 are maintained in position by means of conductors 28 and 29 leading to them 70 respectively, these conductors passing through the walls of tube 8, and being sealed thereto.

For the purposes of television deflection, where- 75 in comparatively low frequency deflecting fields are employed, and the deflection plate capacitance

consequently is of little importance, the first pair of deflecting plates may be very slightly spaced from disk anode 18 and from the last pair of plates. The sensitivity of the two pairs of plates 5 may be made nearly equal, and relatively great, by virtue of their being far removed from the fluorescent screen. It is believed that the new shape and arrangement of deflecting plates that has been disclosed, provides for greater sensitivity, wider angle of deflection of the electronic stream, and less capacitance in the deflecting system than it has been possible to attain heretofore.

A fluorescent screen is shown at 31, located in 15 the usual position. For the fluorescent material, I prefer to use the mineral willemite, according to common practice; but I have discovered that great advantages may be obtained by mixing the fluorescent material with a finely divided substance 20 that is capable of emitting what I will herein call secondary electrons. The metal thorium may be used very satisfactorily for this purpose. Under the bombardment of the electronic stream the usual screen soon becomes negatively charged. This naturally decreases the 25 velocity of the electrons when they are about to impinge upon the screen, by reason of the electrostatic repelling force. The intensity of fluorescence of an ordinary screen will be decreased 30 for this reason. When a secondary electron-emitting substance is used in the screen, however, as many, or more, secondary electrons may be caused to leave the screen as the number of primary electrons in the electronic stream that impinges upon it. In this manner it is possible to 35 keep the fluorescent screen uncharged, or even to cause it to take on a positive charge. This will greatly increase the velocity of the primary electrons when they are about to impinge upon 40 the screen, and will cause the screen to give a much greater fluorescent response.

Obviously, the secondary electrons that are emitted from the screen will be shot off in all 45 directions. They will tend to obstruct the space in front of the screen, and to interfere with the incoming primary electronic stream (although not as seriously as though they were resident upon the screen itself, as usual), unless means are provided to get rid of them. Therefore, I locate a 50 conductive electrode 32 in front of the screen at a slight distance therefrom; and give it a high positive potential, for removing the stray electrons, secondary or otherwise, in its vicinity. This electrode should approximately conform to 55 the shape of the effective area of the screen, and be of such dimensions as not to interfere with the primary electronic stream at its maximum deflection. Electrode 32 may be supported by its conductor 33, led through the glass envelope of 60 the tube 8 and sealed thereto.

In the use of cathode ray tubes that hitherto have been known to the art, the active spot on the fluorescent screen changes in size with the intensity of the electronic stream, and the intensity 65 of the stream is determined by the potential of the grid that is used. I have found that the use of the disk anode 18, in the manner disclosed herein, permits of regulating the size of the screen spot, without noticeably affecting its intensity. If, 70 therefore, the potential supplied to the disk anode is modulated by the incoming signal, in the same manner that the potential of the grid is modulated, the screen spot may be maintained at a constant size.

75 Suitable apparatus for operating my improved

cathode ray tube, is shown diagrammatically in the lower part of Fig. 1. An amplifier tube, for supplying the input signal coming in through conductors 34 and 35, to control grid 13, is shown at 36; and it is provided with an output resistor 37. 5 The incoming signal is fed through a blocking condenser 38, which is of negligible impedance to the frequencies involved; and the signal appears as potential variations at grid 13, over resistor 39.

Vacuum tubes 41 and 42, and their associated apparatus shown, constitute a resistance-capacitance coupled amplifier, used to increase the signal amplitude for impression upon the less sensitive disk anode 18, over resistor 43. The amplification of this amplifying system, and the 10 voltages of batteries 12, 44, and 45, are adjusted to give a constant spot size upon the fluorescent screen; or for any modulated variation of spot size, within limits, that may be desired.

15 It will be appreciated that, if the signal amplitude is great enough, electrodes 13 and 18 can be excited from resistor 37; condenser 46 being connected to the top of resistor 37; and condenser 38, by a tap well toward the bottom thereof; so that a small portion of the signal will be impressed on grid 13. Amplifying tubes 41 and 42, and their associated apparatus, are not required 20 when this is done.

Certain other apparatus for modulating electronic streams, is known to the art, in the use of 25 which the screen spot becomes smaller as it becomes less in intensity. Such apparatus can be used to maintain a constant size of screen spot if employed with a disk anode, such as is illustrated at 18, and if the excitation of this anode 30 is modulated out of phase with respect to the modulation of the grid. This can be accomplished by including only one stage of amplification between the grid and the disk anode, as by connecting condenser 46 to the top of resistor 47, instead 35 of to resistor 48.

An alternate arrangement for maintaining the 40 focus of an electronic stream, which embodies the principles involved in the present invention, is indicated diagrammatically in Fig. 2. In this alternate arrangement, another control electrode 49 is provided, co-axial with grid 13; and a "shield" anode 51, of tubular disk form, is placed 45 between elements 13 and 49 co-axial therewith. Elements 13 and 49 are connected in parallel, and 50 are modulated from a single signal source. The "shield" anode 51 in this case, takes the place of gun anode 15 and of shield 16 of Fig. 1; and, in addition, functions with electrode 49 in the same 55 way as gun anode 15-16, for focusing the electronic stream. This shield anode 51 is held at a positive potential on the order of one-half that of the gun anode 15-16 of Fig. 1. Control electrode 49 thus will act upon slower moving electrons than in the case of the arrangement of 60 Fig. 1, and will have sufficient effect thereupon when excited by only the signal amplitude that is impressed upon control electrode 13.

Control electrode 49 is maintained in its position in tube 8 by means of its conductor 52; and 65 "shield" anode 51 is maintained in position by means of its conductor 53.

It will be understood that, if no anode were used, the electronic stream could emerge from either end of cathode cylinder 8. The use of the anode, 70 however, makes this practically impossible; and only the end of the cathode that is nearest to the anode is effective for emitting electrons. Moreover the left-hand end of cylinder 8 could easily be blocked off, if there appeared to be any prac- 75

tical reason for doing this. In case such blocking off should be done, the interior surface of the closure should be coated with an electron-emitting substance, for increasing the effective capacity of the cathode.

5 In Fig. 1, I have conventionally indicated alternating current generators at 54 and 58, for exciting the respective pairs of deflecting plates 22 and 23, and 26 and 27, in the well known manner. These generators may be of the usual sine wave type; but, for television work, generators that are adapted for producing the so-called "saw-tooth" wave form of energy are greatly to be preferred. When the cathode ray tube 10 is to be used for oscillographic purposes, the potentials to be measured are connected to the respective pairs of deflecting plates 22-23 and 26-27.

15 Having thus fully described and illustrated my invention in a manner that will be readily understood by those familiar with the art involved, I claim:

20 1. A cathode ray tube comprising a cathode and an anode; the cathode being formed of two co-axial nested and spaced tubular shells of conducting material, the shells being conductively connected at one end of each; and substantially parallel for a portion of their lengths, said cathode structure being adapted for passing an electric current through the material thereof for directly heating the inner shell; and the inner surface of the inner shell being adapted for emitting electrons when so heated.

25 2. A cathode ray tube comprising a cathode and an anode; the cathode being formed as a cupped annulus having a cylindrical inmost surface, and with electrical terminals at its inner and outer rims respectively; said surface being adapted for direct heating by passing an electric current 30 through the material of the annulus between said terminals, and for emitting electrons when so heated; and the electrical resistive center of the annulus, with respect to said terminals, being at the inner end of said surface.

35 3. A cathode ray tube comprising a cathode and

an anode; the cathode being formed as a cupped annulus having a cylindrical inmost surface, and with electrical terminals at its inner and outer rims respectively; the intermediate portion of the annulus being in the form of a protruding 5 hollow truncated cone with its apex at the adjacent extremity of said surface; said surface being adapted for direct heating by passing an electric current through the material of the annulus between said terminals, and for emitting electrons 10 when so heated; and the electrical resistive center of the annulus, with respect to said terminals, being at said apex.

4. A cathode ray tube comprising; a cathode; an anode; a pair of narrow parallel-sided and 15 diverging plate electrodes, adapted to deflect in one plane, an electronic stream issuing from the cathode, the plates being similarly disposed on opposite sides of the normal path of said stream; and a second pair of trapezoidally shaped and 20 diverging plate electrodes, adapted to deflect said stream in a different plane, the last said plates being similarly disposed on opposite sides of the normal path of said stream; the spacing between the plates of each of said pairs being least 25 at the point where said stream path enters their respective fields of influence, and only slightly greater than the cross-sectional dimension of said stream; and the angle of divergence between each of said pairs of plates corresponding to the 30 maximum angular deflection of said stream, produced thereby.

5. A cathode ray tube comprising; an anode; a cathode adapted to be held at a large negative potential with respect to the anode and for emitting an electronic stream; and a control grid 35 adapted to be held at an average potential approximating that of the cathode, in the form of a hollow truncated cone, in the path of said stream and co-axial therewith; said control grid 40 having its apex directed toward the cathode and, when energized, being adapted for controlling the intensity of said stream.
